ATTORNEY.

UNITED STATES PATENT OFFICE.

BENJAMIN H. PETLEY, OF SEATTLE, WASHINGTON.

FLUID-PRESSURE REGULATOR.

942,042.

Specification of Letters Patent. Patented Nov. 30, 1909.

Application filed April 20, 1909. Serial No. 491,148.

To all whom it may concern:

Be it known that I, BENJAMIN H. PETLEY, a citizen of the United States, residing at Seattle, in the county of King and State of 5 Washington, have invented certain new and useful Improvements in Fluid-Pressure Regulators, of which the following is a specification.

The object of this invention is the 10 provision of a fluid pressure controller which will serve to regulate the pressure of the fluid delivery irrespective of the initial pressure while the latter is equal to or exceeds the desired delivery pressure and, in the 15 absence of the initial pressure, the apparatus will serve to effect a practically complete discontinuance of the fluid delivery until the pressure thereof is reestablished to the requisite amount.

20 The invention consists in the novel construction and adaptation of devices, as will be hereinafter described with reference to the accompanying drawing which represents in vertical section a regulator constructed 25 in accordance with this invention.

The reference numeral 5 designates a casting provided with a valve chamber 6 and a superposed diaphragm chamber 7 which is 30 communicatingly connected therewith by a duct 8. A cover-part 5' is provided for the chamber 7 and is arranged to be removably secured by clips, such as 9, which engage over the peripheral flange 10 of the cover and a ring 13. Extending transversely 35 across the chamber 7 is a diaphragm 11 which is secured about its circumference between a flange 12 of the casing and the ring 13 which are connected by a plurality of screws 14, as shown. Said screws likewise afford pivotal connections for the clips 9. Said valve chamber 6 is provided with an inlet opening 15 and an outlet opening 16 which are screw-threaded or provided with other means for making pipe connections, 45 and are herein shown in axial alignment with each other, though not necessarily so. Within the valve chamber and intermediate said openings is a partition 17 having an opening 18 constructed to afford a seat 19 below and another seat 20 above the partition.

A stem 21 which is connected with said diaphragm 11, as by socketing in an attachment 22, extends downwardly through 55 said opening 18 and has mounted thereupon valves 23 and 24 which are disposed to co-

operate with the respective seats 19 and 20 to close, upon occasion, the opening between the inlet and outlet sides of said partition. The stem 21 is extended for connection with 60 an ancillary diaphragm 25 which closes an opening 26 in the bottom of the valve chamber and at the inlet side of the partition. Provided below this diaphragm 25 is a chamber 27 having communication through 65 a passage 28 with the outlet side of the partition. A passage 29 and an annular passage 30 communicate with the passage 28 to afford an uninterrupted flow of the fluid from the inlet to the outlet side of the partition. These passages constitute a by-pass 70 which may be regulated as to capacity by an adjustable screw 31 which operates to partially close the passage 29.

Extending through and depending from 75 the cover-part 5' is a tubular element 32 which is provided with a peripheral flange 33 to furnish a chair for limiting the downward movement of an annular shaped weight or heavy body 34. Connected with the 80 diaphragm 11 and extending upwardly through the element 32 is a rod 35 having at its upper extremity an adjustably connected head 36. A standard 37 provided upon the cover part 5' supports by a pivotal 85 pin 38 a dog 39 which, if allowed to be pendent as represented by full lines in the drawing, operates to engage upon the top of the head 36 when the latter descends with the closing of the valve 24 to lock the 90 same against automatically reopening; or the dog may be caused to be inoperative by swinging it over, as indicated by broken lines a, against a stop 40 provided in the 95 standard.

The operation of the invention is as follows: With the valves in the positions as shown in the drawing the invention acts in the capacity of a regulator tending to maintain a uniform outlet fluid pressure and any 100 variation of the latter against the underside of the diaphragm 11 causes a further opening or closing of the valve 23 to bring about such desired delivery pressure. Should the pressure against the underside of the diaphragm 11 be reduced either by a discontinuance of the initial pressure or by an excessive fluid delivery, as may be caused by a broken discharge pipe, until the delivery 105 pressure can no longer support the diaphragm 11 and the attachments thereto, then the valve 24 is caused to close upon its 110

seat 20 and will thus remain until a sufficient pressure against the diaphragm 11 is re-established, provided that the dog 39 is caused to be inoperative, as when the same is thrown over in the position indicated by a. Should the dog be allowed to be operative, as when hanging in the position indicated by full lines in the view, then it will engage over the head 36 coincidently with the closing of the valve 24 to lock the same against reopening until the dog is manually disengaged to release the valve. Assuming that the dog is in its aforesaid inoperative position and all openings in the delivery pipe are closed, then a resumption of the initial pressure and a flow of the fluid through the by-pass connections 29, 30 and 28 will afford a gradual accumulation of pressure at the delivery side which will ultimately affect the diaphragm 11 to reopen the valve 24. The flow of the fluid is accordingly restored through the valve opening and is normally regulated through the agency of the valve 23. Should the delivery pressure exceed a desired amount the diaphragm 11 will be acted upon to close the valve 23 in opposition to the force of the weight 34 which must be overcome before the valve 23 can be closed. The diaphragm 25 serves as a balancing agent with reference to the valves 23 or 24 and with respect to the initial and delivery pressures of the fluid.

What I claim is—

1. The combination of a containing case provided with a valve-chamber having inlet and outlet openings and a partition therebetween which is provided with an opening extending through the partition and having valve-seats at its upper and lower ends, a valve for each of said seats, a chamber communicatively connected with the valve chamber from the outlet side of said partition, a diaphragm extending transversely across the second named chamber, and a stem connected to the diaphragm and with both of said valves, said containing case being provided with a by-pass making continuous connection between the inlet and outlet sides of the partition.
2. The combination of a containing case provided with a valve-chamber having inlet and outlet openings and a partition therebetween which is provided with an opening extending through the partition and having valve-seats at its upper and lower ends, a valve for each of said seats, a by-pass affording continuous communication between the inlet and outlet sides of said partition, a chamber superposed with respect to said valve-chamber and communicatively connected with the latter from both the inlet and the outlet sides of said partition, a diaphragm extending transversely across the second named chamber, a stem connecting the diaphragm directly with both of said

valves for corresponding movements, a chair extending downwardly from said cover, and a weight arranged to be supported by said chair and likewise for engagement by said diaphragm.

3. The combination of a containing case provided with a valve-chamber having inlet and outlet openings and a partition therebetween and provided with an opening extending through the partition and having valve-seats at its upper and lower ends, said containing case being provided with a by-pass making connection between the inlet and outlet sides of the partition, a valve for each of said seats, a chamber superposed with respect to said valve-chamber and communicatively connected with the latter from the outlet side of the partition, a diaphragm extending transversely across the second named chamber, a stem operatively connecting the diaphragm with both of said valves, a rod extending through the cover, an adjustable head upon the rod, and a dog arranged to engage said head when the rod is in its lowermost position.

4. The combination of a containing case provided with a valve-chamber having inlet and outlet openings and a partition therebetween and provided with an opening extending through the partition and having valve-seats at its upper and lower ends, a valve for each of said seats, a chamber superposed with respect to said valve-chamber and communicatively connected with the latter, a cover for the second named chamber, a diaphragm extending transversely across the second named chamber, and between the casing and said cover, means for securing the cover to the casing so that the cover is removable without disturbing the securing of said diaphragm, and a stem operatively connecting the diaphragm with both of said valves.

5. The combination of a containing case provided with a valve chamber having inlet and outlet openings and a partition therebetween and provided with an opening extending through the partition and having valve-seats at its upper and lower ends, a valve for each of said seats, a chamber superposed with respect to said valve-chamber and communicatively connected with the latter from the outlet side of said partition, a diaphragm extending transversely across the second named chamber, a stem operatively connecting the diaphragm with both of said valves, and another diaphragm operatively connected with said stem and arranged to be exposed to fluid pressures which prevail at the inlet and outlet sides of the partition.

6. The combination of a containing case provided with a valve-chamber having inlet and outlet openings and a partition therebetween and provided with an opening extending through the partition and having valve-

- seats at its upper and lower ends, a valve for each of said seats, a chamber superposed with respect to said valve-chamber and communicatively connected with the latter from the outlet side of said partition, a diaphragm extending transversely across the second named chamber, and a means arranged to secure said valves against rising when in their lowermost positions.
10. 7. The combination of a containing case provided with a valve-chamber having inlet and outlet openings and a partition therebetween and provided with an opening extending through the partition and having valve-seats at its upper and lower ends, a valve for each of said seats, a chamber superposed with respect to said valve-chamber and communicatively connected with the latter from the outlet side of the partition, a diaphragm extending transversely across the second named chamber, a stem operatively connecting the diaphragm with both of said valves, means arranged to secure said valves against rising when in their lowermost positions,
15. 25. a weight arranged to be engaged by said diaphragm, and another diaphragm operatively connected with said stem and arranged to be exposed to fluid pressures which prevail at the inlet and outlet sides of the partition.
20. 30. 8. The combination of a containing case provided with a valve-chamber having inlet and outlet openings and a partition therebetween and provided with an opening extending through the partition and having valve-seats at its upper and lower ends, a valve for each of said seats, a chamber superposed with respect to said valve-chamber and communicatively connected with the latter from the outlet side of the partition, a cover for the second named chamber, clip-devices for detachably securing said cover to the casing, a diaphragm extending transversely across the second named chamber, a stem operatively connecting the diaphragm with both of said valves, a chair extending down-wardly from said cover, a weight arranged to be supported by said chair, and likewise for engagement with said diaphragm, a rod extending through the cover, an adjustable head upon the rod, a dog arranged to engage said head when the rod is in its lowermost position, another diaphragm operatively connected with said stem and arranged to be exposed to fluid pressures which prevail at the inlet and outlet sides of said partition, said containing case being provided with a by-pass making connection between the inlet and outlet sides of the partition, and a means for regulating the capacity of said by-pass.
25. 35. 9. The combination of a casing provided with a valve-chamber having inlet and outlet openings and a valve seat therebetween, a valve, two diaphragms which are respectively exposed to the fluid pressures prevailing at the inlet and outlet sides of said valve seat, and a stem connecting said valve with both of the diaphragms and whereby the valve is caused to close upon said seat when the fluid pressure at the delivery side of the seat is decreased to a predetermined amount.
40. 45. 10. The combination of a casing provided with a valve-chamber having inlet and outlet openings and a valve-seat therebetween, a valve, a stem for the valve, a diaphragm connected with the valve for operating the latter to close upon said seat when the fluid pressure at the delivery side of the seat is decreased to a predetermined amount, and a by-pass for conducting a fluid continuously from the inlet to the outlet sides of said seat whereby the fluid pressure at the outlet side will be built up to influence said diaphragm and cause the automatic reopening of the valve when the pressure at the outlet side is restored to a predetermined amount.
